UNITED STATES PATENT OFFICE.

CHARLES C. RUEGER, OF BUTTE, MONTANA.

STAMP-TAPPET.

SPECIFICATION forming part of Letters Patent No. 707,259, dated August 19, 1902.

Application filed June 5, 1901. Serial No. 63,240. (No model.)

To all whom it may concern:

Be it known that I, CHARLES C. RUEGER, a citizen of the United States, residing at Butte, county of Silverbow, State of Montana, have 5 invented an Improvement in Stamp-Tappets; and I hereby declare the following to be a full, clear, and exact description of the same.

My invention relates to an improvement in tappets such as are secured to the stems of 10 ore-crushing stamps in such position as to be engaged by cams upon a cam-shaft, which serve to alternately raise the stamps and release them, so that they may drop and crush the ore within the mortar of the battery.

15 My invention consists in an improved means for securing the tappet upon the stem and in details of construction which will be more fully explained by reference to the accompanying drawings, in which—

20 Figure 1 is a vertical section of my invention, taken on the line $x-x$ of Fig. 2. Fig. 2 is a horizontal section on the line $y-y$ of Fig. 1. Figs. 3 and 4 are horizontal sections illustrating modified bores of the tappet. Fig. 5 25 is a horizontal section of the tappet similar to Fig. 2 and showing the stem, the gib, and the key in dotted lines.

In stamp-tappets as ordinarily used great strain must be put upon the gib and keys in 30 order to hold the tappet so firmly to the stem that it will not slip when the stamp is in operation, and this strain tends to rupture the key-seat besides damaging the gibs and keys on account of the hard driving which is necessary to hold the parts firmly in place. In 35 consequence of this the grip of the gib upon the stem only extends to a short distance beyond the bearing area of the key upon its back, and by reason of the loose fit of the 40 tappet upon the stem there is but a very small bearing-surface between the outside of the stem and the inside of the tappet-bore at the point opposite the key-seat.

It is the object of my invention to provide 45 an improved means for securing the tappets to the stems, to increase the bearing-surface between the stem and tappet, and to increase the power of the gib and key when driven in opposition to this surface.

50 In my invention, A is a stamp-stem, and B the tappet. Instead of using one gib and two or three keys I employ independent gibs

2, one for each key 3, and the key is made of such size that it bears upon the entire back of the gib. The gib is a block of ample size 55 made of tough cast-iron or of cast-steel, requiring only such finishing as can be readily done with a grinding-wheel. The openings transversely of the tappet which form the key-seats are so proportioned that the gib-block of each can be inserted or removed through the large end of this opening or key chamber. This obviates the necessity of removing the whole tappet from the stem in order to exchange a gib. The key besides having a very large bearing-surface on the smooth back of the gib-block has a very large planed seat in the keyway. The key being about double the usual size is very stiff and offers a corresponding resistance to deformation. Ordinarily the tappet has a uniform cylindrical bore, and this fits loosely upon the stamp-stem until the keys are driven. The result is 60 that when the tappet is keyed on the holding-surfaces are only that part of the gib which 65 may be in contact with the stem and a narrow strip of the bore of the tappet upon the opposite side of the stem, and in order to prevent the tappet from shifting the keys must be driven 70 very hard with corresponding detriment to 75 the parts. In my tappet the bore is in the form of segments of cylinders of different radius. The radius of the part 4 is slightly less than the radius of the stamp-stem, this part being upon the opposite side from the key-seats, where the radius of the part 5, which corresponds with the side on which the key-seats are, is correspondingly of larger diameter than that of the stamp-stem. The side 80 opposite the gib is bored out to a very tight 85 fit on the stem, so that the stem will fully seat in the tappet only when driven home with the keys. The stem then has a bearing 90 at least ten times as great as in the old style of bore, the tappet clamping it closely around 95 a considerable portion of the circumference, and it is held very tightly in place. In consequence of this a very moderate driving of the keys will hold the tappet very securely. The space on the gib side being so much 100 larger is entirely free when the keys are withdrawn, and the space between the stem and the tappet is so large on this side that dust and dirt will not lodge and pack therein, as

it will easily drop out at the bottom. Consequently when the keys are withdrawn a few blows with a heavy hammer upon the key side of the tappet will force it away from its hold upon the stem, and the larger space into which the stem is thus forced allows the tappet to be moved easily to any desired point for reseating.

In the modification shown in Fig. 3 a recess 5 5' is cast in the seat 4 directly opposite the gibbs, and this insures a perfect, although somewhat reduced, bearing for the stem, which is of advantage if it should have a loose fit.

15 In Fig. 4 the clearance is provided by two equal parallel bores intersecting each other and with the ridges at the junctions cut out, or that part of the bore contiguous to the gibbs may be made of larger radius than the part 20 opposite to them but intersecting the opposite side of the bore in which the stamp-stem fits and is normally locked by the gibbs and key.

In either construction the removal of the gibbs and key permits the stem to be disengaged from its seat.

Having thus described my invention, what I claim as new, and desire to secure by Letters Patent, is—

1. A stamp-stem tappet adapted to receive 30 independent and separated gibbs and keys upon one side, and having the bore opposite the gibbs of less, and the bore upon the side adjacent to the keys of greater diameter than that of the stamp-stem upon which the tappet 35 is fitted.

2. A stamp-tappet having a bore longitudinally through it approximately half of said bore being of such radius as to fit tightly

about the stem, and the other and opposite portion of the bore having a larger diameter 40 to form a clearance between itself and the stem, keyways passing through the tappet at two or more points removed from each other upon the side contiguous to the larger bore, and gibbs and keys by which the smaller part 45 of the bore is caused to seat about the stamp-stem.

3. A stamp-tappet having a longitudinal bore of two different radii, the smaller of which is adapted to seat tightly around the 50 stamp-stem, openings made transversely through the tappet upon the opposite side, gibbs fitting said openings, and occupying portions only of the clearance-space formed by the larger bore, and seating against the stamp-stem, and independent keys for each gib 55 adapted to lock them in position.

4. A stamp-tappet having a longitudinal bore, one portion of which is of smaller radius than that of the stamp-stem, and the opposite portion of larger radius, independent gibbs and chambers removed from each other and into which they fit in the portion opposite the smaller portion of the bore, keys bearing on approximately the entire back 65 surface of the gibbs, and keyways through which they are driven to force the gibbs against the stem and seat the latter in the opposing smaller bore of the tappet.

In witness whereof I have hereunto set my 70 hand.

CHARLES C. RUEGER.
